UNITED STATES PATENT OFFICE

REINHOLD J. SWANSON, OF CHICAGO, ILLINOIS

DESIGN FOR A WRIST COMPACT

Application filed April 24, 1931. Serial No. 39,610. Term of patent 14 years.

To all whom it may concern:

Be it known that I, REINHOLD J. SWANSON, a subject of the King of Sweden, but having announced my intention to become a citizen of the United States, residing at Chicago, in the county of Cook, and State of Illinois, have invented a new, original, and ornamental Design for Wrist Compacts, of which the following is a specification, reference being had to the accompanying drawings, forming a part thereof, wherein

Fig. 1 is a perspective view of the compact;
Fig. 2 is a plan view thereof; and
Fig. 3 is an end elevational view.

The invention includes a rigid body, substantially elliptical in plan, having a concave under surface, and a circular closure cap at the center of its upper surface of a diameter only slightly less than the length of the transverse axis of the body, the convex side walls of the body meeting the under surface in a relatively well defined line or edge.

I claim:

The ornamental design for a wrist compact, as shown and described.

REINHOLD J. SWANSON.
